DEVICE FOR INSTALLING AND REMOVING
LAMP TUBES

Lyle B. Quick, New Britain, Conn.

Application November 17, 1943, Serial No. 510,632

7 Claims. (Cl. 294—20)

This invention relates to a device for inserting lamp tubes into, and removing them from, fixtures located adjacent the ceiling of a room or any other elevated position or inaccessible place beyond the reach of a person attending the same.

As it is well known, lamp tubes, such as tubes of the fluorescent type, are now in general use in factories and buildings generally, and the fixtures for such tubes are usually suspended or hung from the ceiling beyond the reach of a person designated to take care of them. In many factories, a very great number of such lamps are employed and, as these lamps require frequent replacements, a considerable expense is involved in installing and servicing them, particularly where it is necessary to employ ladders and the like in order to reach them.

The aim of the present invention is to provide a simple device by means of which lamp tubes may be very quickly and easily installed and removed by a person standing on the floor, thus eliminating the use of ladders and the like and effecting a considerable saving in expense and manpower in servicing the lamps.

A further aim of the invention is to provide a device of this character having various features of novelty and advantage and which is particularly characterized by its simplicity in construction, its lightness in weight, its economy in manufacture, and its effectiveness in use.

Other objects will be in part obvious and in part pointed out more in detail hereinafter.

The invention accordingly consists in the features of construction, combination of elements and arrangement of parts which will be exemplified in the construction hereinafter set forth and the scope of the application of which will be indicated in the appended claims.

In the accompanying drawing, wherein I have shown one embodiment which the present invention may take:

Figure 1 is a view showing a lamp fixture suspended from a ceiling and also showing my improved device in front elevation engaged with the lamp tube preliminary to giving the same a quarter turn about its axis in order to remove it;

Fig. 2 is a vertical sectional view of the arrangement shown in Fig. 1, this view being taken substantially on line 2—2 of Fig. 1 and looking in the direction of the arrows;

Fig. 3 is a view similar to Fig. 2 but showing, by broken lines, the position of the device after the lamp tube has been given a quarter turn in

its sockets and also showing, in full lines, the device after it has been moved down to withdraw the tube from the fixture; and

Fig. 4 is an end elevational view of my device, a lamp tube also being shown in end elevation.

Referring to the drawing in detail, I have shown, for illustrative purposes in Figs. 1, 2, and 3, a lamp fixture of a type now commonly in use. This fixture includes a housing 10 suspended from a ceiling by hangers 11, a reflector 12 secured to the housing, and two brackets or socket members 13, 13, depending from the housing and located adjacent the opposite ends of the reflector. The numeral 14 designates the fluorescent lamp tube which, as usual, has at each end a pair of pins 15. The pins of each pair are disposed to opposite sides of the axis of the tube. Each of the brackets 13 has, on its inner face, a recess or socket 16 into which extends a pair of resilient contact fingers 17. Leading downward from each socket is an entrance groove 16a. The fingers 17 are to opposite sides of a central stud 18 which is slotted vertically as at 19. When it is desired to install a lamp between the brackets, the lamp is moved from the full line position shown in Fig. 3 to the dotted line position shown in that figure, and then it is turned 90° about its axis so as to engage the pins 15 with the fingers 17 in the manner shown in Fig. 2. To remove the lamp, this series of operations is reversed.

Referring now to the device of the present invention, the same has a rod or pole 20 which preferably is made of a series of sections with quick detachable connections therebetween whereby the rod may have any desired length depending on the height at which the lamp is located above the floor. In the present instance, two such sections 20a and 20b are shown. The sections of the rod 20 may be square in cross section and may be detachably connected together by an arrangement such as shown in Fig. 1. In this figure, it will be seen that the lower end of the section 20a fits within a sleeve 21 secured to the upper end of the section 20b. This sleeve carries a cross pin 22, and the lower end of the section 20a is slotted or grooved as at 23 so as to accommodate this pin.

The upper end of the rod 20 carries a stud 25 which constitutes a fixed pivot for a bracket 26 and an anchor for a bevel gear 27. The pin or stud 25 extends axially beyond the upper end of the section 20a of the pole and is secured against rotation relative to the pole by a cross pin 29. The bracket 26 comprises a U-shaped

member having a base 26a and vertically extending side arms 26b. The base 26a has a central opening which rotatably receives the pivot stud 25. The base 26a is located between the end surface of the pole and the gear 27. The stud has a head 28 beneath which the gear is keyed to the stud as at 27'. The side arms 26b have aligned openings in which is journaled a shaft 30 which is here in the form of a bolt having a nut 31. Secured to the shaft 30, as by means of a key 32', is a bevel gear 32 meshing with the bevel gear 27. Mounted on the bolt and rigidly connected with the gear 32, as by means of the key 32', is a yoke 33 comprising a member of inverted U-shape. This yoke has a connecting portion 33a and depending arms 33b, the latter being provided with apertures which closely receive the shaft 30. The yoke is of such length that it fits between arms 26b of the bracket 26. Between the nut 31 and the right hand arm 26b of the bracket 26 is a friction device which is here shown as being in the form of a spring washer 35. This washer frictionally maintains the yoke in any desired angular position with respect to the bracket 26. Secured to the connecting portion 33a of the yoke, and extending at right angles to the length of the rod 20, is a bar 40, and this bar is provided, adjacent its opposite ends, with spring clips or clasps 41 which are adapted to embrace the lamp tube 14 adjacent the ends thereof. In the present instance, each of these clips has a pair of particircular spring fingers, the free ends of which are turned outwardly as at 42. Stop pins 45 carried by the bracket 26 serve to limit the extent to which the yoke may be pivoted about the axis provided by the shaft 30.

With the structure described, when it is desired to remove a lamp from an overhead fixture, the yoke is in the position shown in Figs. 1 and 2 and wherein the connecting portion 33a of the yoke is parallel to the base 26a of the bracket. The lower end of the rod is gripped, and the device is raised so as to slip the clips about the ends of the lamp tube. Then the rod is manually turned about its longitudinal axis and, since the drive gear 27 is fixed to the stud 25 and the stud is fixed to the rod 20, this gear will rotate with the rod. Since the engagement of the clips 41 with the lamp prevents the yoke and the bracket from rotating with the rod, the gear 27 causes the gear 32 to rotate so that the assembly (comprising this gear 32, the bolt 30, the yoke 33, and the bar 40) will pivot about the axis of the bolt 30, thus bringing the assembly from the upright position shown in Fig. 2 to the lateral position shown by dotted lines in Fig. 3. Further, since the spring clips frictionally embrace the tube, the tube will be given a quarter turn so that the pins 45 projecting from the ends of the tube will be brought into registry with the entrance groove 16a and the slot 19. The device is now lowered so as to remove the lamp tube from the brackets. When it is desired to replace the lamp tube, the sequence of operations just described is reversed. That is to say, the lamp tube is positioned within the clips when the yoke is in the position shown by full lines in Fig. 3, then the device is raised to the broken line position as shown in that figure, and, finally, the rod is turned counterclockwise about its axis whereupon the lamp tube is given a quarter turn from the position shown in Fig. 3 to that shown in Fig. 2. The

device may now be pulled down so as to slip the clips off of the tube.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A device for installing and removing lamp tubes comprising a rod, a member journaled on one end of said rod and about the longitudinal axis thereof, a second member journaled on said first member for limited pivotal movement about an axis at right angles to the axis of rotation of said rod relative to said first member, a pair of spaced apart aligned clasps fixedly carried by said second member and adapted to frictionally embrace a lamp tube, and gear means between said rod and second member for causing pivotal movement of said second member about its axis when said rod is turned about its longitudinal axis.

2. A device for installing and removing lamp tubes comprising a rod, a member mounted on one end thereof for relative rotation about the longitudinal axis of the rod, a second member journaled on said first member for limited pivotal movement about an axis at right angles to the longitudinal axis of said rod, means fixedly carried by said second member for clasping a lamp tube, a bevel gear fixed to said end of said rod so as to rotate therewith, and a second bevel gear meshing with said first one and fixed to said second member so as to rotate therewith about the axis of pivot thereof when said rod and first gear are turned about the axis of said rod.

3. A device for installing and removing lamp tubes comprising a rod, a member journaled on one end thereof for relative rotation about the longitudinal axis of the rod, a second member journaled on said first member for limited pivotal movement about an axis at right angles to the axis of rotation of said rod, means for frictionally restraining pivotal movement of said second member, a pair of spaced apart aligned clasps fixedly carried by said second member and adapted to frictionally embrace a lamp tube, and gear means between said rod and second member for causing pivotal movement of said second member about its axis when said rod is turned about its longitudinal axis.

4. A device for installing and removing lamp tubes comprising a rod, a member mounted on one end thereof for relative rotation about the longitudinal axis of the rod, a second member journaled on said first member for limited pivotal movement about an axis at right angles to the axis of rotation of said rod, a pair of spring clasps fixedly carried by, and spaced apart on a line parallel to the axis of pivot of, said second member for clasping a lamp tube, a bevel gear fixed to said end of said rod so as to rotate therewith, and a second bevel gear meshing with said first one and fixed to said second member so as to rotate therewith about the axis of pivot thereof

when said rod and first gear are turned about the axis of said rod.

5. A device for installing and removing lamp tubes comprising a rod, a fixed stud projecting axially from one end of said rod, a bracket journaled on said stud, a bevel gear fixed to said stud, a shaft journaled in said bracket and disposed at right angles to the length of said rod, a yoke fixed to said shaft, a bevel gear fixed to said shaft and meshing with said first gear, a bar fixed to said yoke in parallelism with said shaft, and a pair of spring clasps secured to said bar adjacent the opposite ends thereof.

6. A device for installing and removing lamp tubes comprising a rod, a fixed stud projecting axially from one end of said rod, a bracket journaled on said stud, a bevel gear fixed to said stud, a shaft journaled in said bracket and disposed at right angles to the length of said rod, a yoke fixed to said shaft, a bevel gear fixed to said shaft and meshing with said first gear, a bar fixed to said yoke in parallelism with said shaft, a pair of spring clasps secured to said bar adjacent the opposite ends thereof, and a spring washer between

said shaft and bracket for frictionally restraining pivotal movement of said yoke.

7. A device for installing and removing lamp tubes comprising a rod, a fixed stud projecting axially from one end of said rod, a bevel gear fixed to said stud, a U-shaped bracket having a base and a pair of side arms, the base being positioned between said end of the rod and said gear and being journaled on said stud, a shaft journaled in the side arms of said bracket and intersecting the longitudinal axis of said rod at right angles, an inverted U-shaped yoke having a connecting portion and side arms, said side arms being apertured to receive said shaft and said yoke being secured to said shaft, a bevel gear fixed to said shaft and meshing with said first mentioned gear, a friction washer between said shaft and said bracket for frictionally restraining pivotal movement of said yoke, a bar secured to the connecting portion of said yoke and parallel to said shaft, and means carried by said bar for gripping a lamp tube.

LYLE B. QUICK.
